UNITED STATES PATENT OFFICE.

BENJAMIN C. VANDUZEN, OF WINTON PLACE, OHIO, ASSIGNOR OF ONE-HALF TO EZRA W. VANDUZEN, OF NEWPORT, KENTUCKY.

GAS OR GASOLINE ENGINE.

SPECIFICATION forming part of Letters Patent No. 448,386, dated March 17, 1891.

Application filed February 1, 1890. Serial No. 338,901. (No model.)

To all whom it may concern:

Be it known that I, BENJAMIN C. VANDUZEN, a citizen of the United States, and a resident of the town of Winton Place, in the 5 county of Hamilton and State of Ohio, have invented certain new and useful Improvements in Gas and Gasoline Engines, of which the following is a specification.

The various features of my invention and 10 the several advantages resulting from their use, conjointly or otherwise, will be apparent from the following specification and claims.

In the accompanying drawings, making 15 part of this specification, and to which reference is hereby made, Figure 1, Sheet 1, is a side elevation of an engine embodying my improvements. Fig. 2, Sheet 2, is a vertical longitudinal section of the said engine, the section being taken at the dotted line 2 2 of 20 Fig. 3. Fig. 3, Sheet 3, is a vertical transverse section taken at the dotted line 3 3 of Fig. 1, that face of the section which is at the right hand in Fig. 1 being the one shown. The mechanism which is within the bed-plate 25 is omitted from this sectional view. Fig. 4, Sheet 3, is a central vertical longitudinal section of the valves and gas-lighting device. This section is taken in the plane passing through the dotted lines 4 4 of Fig. 3. Fig. 5, 30 Sheet 1, is a vertical section of the carburetor of said engine, the plane of the section being at right angles to the vertical longitudinal plane of the bed-plate of the engine. The carburetor is here shown on an enlarged scale. Fig. 6, Sheet 1, is a horizontal section taken 35 at the line 6 6 of Fig. 5, the spectator looking down at the lower face of said section. Fig. 7, Sheet 1, is a top view of said carburetor and of its gasoline-supply pipe and of the cock 40 controlling the admission of gasoline through said pipe to the carburetor. Fig. 8, Sheet 3, is a vertical central section of the preferred description of burner employed to heat the tube for igniting the gas in my engine, said figure being on an enlarged scale. Fig. 9, Sheet 3, is a front end view of the adjacent 45 end of the valve-stem and of the stud lifted by the eccentric and employed to operate the valve-stem, and also showing in dotted lines 50 the position of the valve-stem when moved

out of working contact with said stud by the governor. Fig. 10, Sheet 2, is a top view of the hinged pieces lifted by one of the cams, and which pieces respectively operate their respective valve - stems, hereinafter mentioned. Fig. 11, Sheet 2, is a front end view of the piece which lifts the stem of the ignitor-valve, and also showing the cam-roller of said piece and also the lower end of the said valve-stem. Fig. 12, Sheet 2, is a top view of the 60 device shown in Fig. 11 and showing the cam-roller by dotted lines and showing in cross horizontal section the lug whereby the said device is supported. Fig. 13, Sheet 2, is an elevation of that side of the device shown in 65 Fig. 11, which is on the right hand in Fig. 3. Fig. 14, Sheet 2, shows in side elevation the cam for operating the inlet and discharge valves and also the cam for operating the valve of the ignitor. Fig. 15, Sheet 3, is a 70 top view of a convenient device for holding the valve-stem, whereby gas is fed to the engine in contact with the lifting-stud, insuring the operation of said valve and the admission of gas to the engine when the latter is started. 75

A suitable bed or frame-work A supports the machine. The preferred form of this bed-plate consists of sides A' A', ends A² A², and top A³, provided with opening A⁴ to receive the lower end of the cylinder, and with 80 opening A⁵ to allow the crank and pitman to operate through it. The top is further provided with a depression A⁶, in which are the lower portions of the eccentrics or valve-trip- 85 pers.

Each end A² of the frame A is provided with an opening A⁷, and through the latter the mechanism within said frame can be reached. These openings A⁷ A⁷ are preferably closed by suitable doors A⁸, one of which 90 is shown covering the opening A⁷ in that end of the frame A which is on the right hand in Figs. 1 and 2. The bottom edges of the frame A are provided with flanges A⁹ for rendering the frame stronger and more stable. 95

B represents the vertical cylinder in which the gas is exploded. This cylinder contains a piston B', suitably packed, preferably as shown, by rings B², of cast-iron.

B³ B³ are springs or oil-fingers, whose upper 100

ends are attached to the piston-head and move with it. The lower or free ends of these oil-fingers press against the inside of the cylinder B and distribute over it the oil 5 lifted by said fingers from the annular oil-chamber B⁵ below the cylinder. This oil-chamber B⁵ surrounds the pitman and the oil-fingers B³ dip into the oil it contains at each depression of the piston.

- 10 A recess B⁴, located in the lower side of the piston, receives the upper end of the pitman C. The upper end of this pitman is provided with journal-bearings in a suitable box, the journal-bearings engaging a cross-journal C', located in said recess B⁴, and having its respective ends fixed in the respective opposite sides of the recess. The lower end of the cylinder B is open, and through this lower open end of the cylinder the pitman C extends. 15
- 15 The lower end of the pitman is pivotally connected (preferably by journal-boxes in the usual manner) at D' with the adjacent end of a walking-beam D. This walking-beam oscillates on a pivotal fulcrum D², the ends 20 of said fulcrum being supported in journal-bearings D³, upheld by the frame-work A. The other end of the walking-beam D is pivotally connected at D⁴ to the lower end of a second pitman E. The upper end of this 25 pitman E is pivotally connected to the free end of the crank F. The crank-shaft F' is supported in journal-bearings F², supported on pillow-blocks resting on and bolted or otherwise suitably secured to the frame A. 30
- 35 This shaft F' carries the pulley or gear, whereby the power generated by the engine is communicated to the mechanism which it is desired to thereby operate. On this shaft F' is preferably fixed, as shown, the fly or 40 momentum wheel F³ for carrying the crank F past its dead-centers and also for rendering the action of the engine uniform.

The valve G for controlling the inflow of gas into the cylinder B and for enabling the 45 gas to be properly mixed with air is shown in section at the left hand in Fig. 4. The valve H for controlling the outflow of the volatile products of combustion after the gas has been burned in the cylinder B is shown in section 50 at the right hand in Fig. 4. The construction of this valve G is fully set forth in an application for a patent therefor filed February 2, 1888, and bearing the serial number 262,812. A brief description of said valve 55 will here suffice, viz: The valve-seat G' is provided with oblique passage-ways G², which latter convey gas from a conduit G³ to the surface of the valve-seat. This conduit G³ is preferably annular and surrounds an inlet or 60 passage-way G⁴ of the valve. This passage G⁴ is connected with the outer air by means of the conduit L'. The stem G⁵ of the valve slides through and is supported by the cylindrical bearing G⁶. Thence the valve-stem G⁵ 65 extends upward and terminates at the valve-piece G⁷, to which latter it is attached.

The gas-chamber G⁸ receives gas from the

gas-supply pipe G⁹. The gas supplied thereto will usually be that received from the gas-main or equivalent source. As the valve G⁷ lifts, this gas passes up through the oblique 70 passages G² to the surface of the valve-seat. At the same time air passes through the inlet passage-way G⁴, and meeting with the said gas at the valve-seat mixes therewith. The 75 gas thus mixed with air enters the conduit I and passes to the cylinder B.

The exhaust-valve H consists of a valve-seat H' and a valve-piece H², supported on a stem H³, sliding through and supported by a 80 cylindrical bearing H⁴. The opening in the valve-seat communicates with the conduit I above and with the exhaust passage-way H⁵ below, the latter communicating through opening H⁶ with the open air or with a suitable 85 exhaust-pipe.

The lighter—that is to say, the device for igniting the gas in the cylinder B, and thereby operating the piston of said cylinder in the manner hereinafter set forth—is as follows: J is a valve, constructed substantially as follows: J' is the valve-seat, and J⁶ indicates the valve-piece which rests on said seat. The valve-piece J⁶ is supported by a stem J³, and the latter slides in and is steadied by a 90 cylindrical support J⁴. The lower end of this support J⁴ is preferably provided with a stuffing-box J⁵ located around the stem J³. For compactness of construction the valve-support J⁴ passes through the conduit I; but it occupies 95 only a portion of the width of this conduit, and offers no sensible obstruction to the passage of the gas through conduit I from the valve G to the cylinder B. The space J⁷ above valve J is, when the valve-piece J⁶ lifts, connected to 100 conduit I by the passages J⁸ J⁹, opening at one end into the conduit I and at the other into the space left vacant as the valve J⁶ lifts, and which latter space then connects the openings J⁸ with the space J⁷. K indicates a vertical cylinder, located above valve 105 J, and, preferably, for convenience, secured to the upper part of the shell of conduit I by means of flanges on said cylinder bolted to said shell. Through this cylinder K passes 110 a vertical pipe K', the latter occupying the center of this cylinder. The lower end of this pipe K' communicates with the space J⁷ above valve J, and the upper portion of said pipe is projected beyond the upper end of 115 cylinder K and terminates in the hollow sphere K². This sphere has a small opening K³ in its upper extremity for allowing the bad gas—viz., the dead or consumed gas, otherwise known as the “volatile products of combustion,” generated in the space J⁷, when gas 120 is ignited therein by the red-hot pipe K'—to escape through said pipe K' into the outer air. This bad gas escapes from the space J⁷ when the valve J⁶ is raised, for the reason 125 that when the valve J⁶ is elevated the good gas from conduit I is forced into the space J⁷ and expels the bad gas therein through opening K³. At the same time the good gas present 130

in said space J^1 is ignited by the red-hot pipe K' , and lights the gas in conduit I , first lighting the gas in the space at the side of and below the lifted valve J^6 . The gas thus 5 lighted in this space lights the gas in passages J^8 , and this in turn lights the gas in the cylinder B over the piston B' .

Against the interior of the cylinder K , immediately above the point where the pipe K^5 enters into it, is located an inner lining K^4 of a non-heating conducting material, preferably of asbestos. This lining performs the office of preventing the pipe K from burning out, and also concentrates the heat of the 10 burner upon the lighting-tube K' , thereby assisting in keeping it red-hot. This burner will now be described. Into the space K^4 of the cylinder K the free end of the gas-pipe K^5 enters. This pipe receives gas from a suitable source, preferably from the same source as does the gas-supply pipe G^9 . The inflow of gas through pipe K^5 is controlled by a suitable cock K^{10} . (See Fig. 4.) The pipe is supported in any desired manner—for example, 15 by a vertical rod K^6 , fixed to the top of the shell of gas-conduit I . Combined with this pipe is a Bunsen burner, of which K^{11} is a diaphragm in pipe K^5 . This diaphragm is centrally pierced by a fine opening K^9 , 20 through which a stream of gas passes. This stream of gas is ignited at that end of the pipe K^5 which is adjacent to the space K^4 . Openings K^8 in the pipe K^5 to the right of the diaphragm—viz., on the flame side of the latter—connect the interior of the pipe with the outer air. Oxygen from the outer air is thereby supplied to the burner to feed the combustion. The amount of air (and consequently the amount of oxygen) supplied to 25 the burner is regulated by the screw-ring K^7 , which latter can by rotation be advanced over the openings K^8 to a greater or less degree, as desired, and thus diminish at will their size as regards the inflow of air to the burner. 30 Air is further supplied to the space K^4 , into which the flame of the burner enters, by means of the annular opening K^{12} in pipe K^{13} , which last-named pipe the pipe K^5 enters. Thus the flame is fully supplied with oxygen. By 35 this flame that part of the pipe K' which is opposite to the pipe K^5 is heated to a red heat. The passage of gas through gas-pipe G^9 into the gas-engine is controlled by a suitable valve, as G^{10} , located between the gas-pipe G^9 and the gas-supply pipe G^{11} , from 40 which the gas is supplied from the gas-main or equivalent source.

When gasoline is to be employed to operate my engine, it must first be converted into gas. 45 Such conversion is preferably accomplished by a novel and useful carburetor of my own invention, one especially adapted for use in connection with gas-engines. This carburetor is constructed as follows, viz: L indicates a hollow cylinder, the interior space of which is near the bottom of the said cylinder connected to the conduit L' , the latter being

connected at its other end, as specified, with the space G^4 below the valve G . In other words, the preferred connection of this carburetor to the inlet-valve G is through the conduit L' . When this carburetor is employed and connected to the inlet-pipe L' , then the inlet gas-pipe G^9 G^{11} will be closed by the cock G^{10} , or other suitable means. Within cylinder L and concentric therewith is a smaller pipe L^2 . The lower end of this pipe L^2 passes through the bottom of cylinder L , and the interior of said pipe L^2 there communicates with the outer air. This pipe L^2 is held in 50 position within cylinder L by any suitable means, the preferred means being those shown—viz., the flange L^3 of the bottom of the cylinder L . This flange L^3 extends downwardly from and below the bottom of cylinder L , and embraces pipe L^2 and holds the latter firmly in its upright position. The space in cylinder L around pipe L^2 has no direct communication with the outside air except at the top of pipe L^2 , as is now to be 55 specified. The top of pipe L^2 is located some distance below the top of cylinder L , and it is covered by a valve L^4 at all times, except when this valve lifts. The valve L^4 has a valve-stem L^5 , which passes into the extension L^6 of the valve-chamber L^{10} . This extension L^6 is screwed into the upper end or head of cylinder L . The valve-stem L^5 abuts against the lower end of the stem L^{14} of a valve L^7 also located in said extension L^6 . The valve L^7 has a seat at the upper end of the extension L^6 in chamber L^{10} . The entire length of the valve-stem L^5 and the stem of valve L^7 is such that the valve L^4 is at rest on the top of pipe L^2 at the same time that the valve L^7 is seated on the seat of extension L^6 . The periphery of the valve L^7 is provided with vertical grooves L^8 , and these connect with vertical grooves L^9 , located in the stem L^{14} of valve L^7 and connected to like grooves L^9 of the valve-stem L^5 . These 100 grooves L^8 L^9 connect the space L^{10} above the valve L^7 with the interior space of cylinder L . A suitable gasoline-inlet pipe L^{11} communicates with said space L^{10} over the valve L^7 . The flow of gasoline through this inlet-pipe L^{11} is 105 controlled by a suitable cock, as L^{12} . The interior annular space in cylinder L is in part occupied by layers or divisions L^{13} of fine gauze-wire for subdividing the gasoline passing through them into minute subdivisions, and 110 thereby enabling the air to come into contact with a very large surface of said gasoline, and thereby more fully and extensively carburet the said air.

At this stage of the specification I will 115 describe the operation of the carburetor. Each time the inlet-valve G is raised it allows gas to be drawn into the cylinder B , and the simultaneous depression of piston B' creates a partial vacuum in the pipe L' . A suction is 120 thereby created in said pipe L' . The external air in said pipe L^2 then lifts valve L^4 and also valve L^7 . The gasoline in space L^{10} runs down through grooves L^8 and between the

valve L⁷ and its valve-seat and through the grooves L⁹ into cylinder L. The passage of this gasoline through said grooves into cylinder B is immediately hastened by the suction 5 created in pipe L' and in cylinder L, heretofore mentioned. This gasoline thus entering cylinder L falls upon the valve L⁴ and runs down the inclined top of the latter and falls over its peripheral edge. As it here falls over 10 said edge of this lifted valve L⁴, it is forcibly commingled with the air which rushes into cylinder L out of pipe L², directly beneath this edge of said valve L⁴. This commingled air and gas is rapidly carried through the 15 gauze rings L¹³, thereby still further commingling the gasoline and the air therein. The vapor consisting of the air thus enriched or carbureted by the vapor from the gasoline passes into pipe L' and finds its way 20 through valve G and conduit I into the cylinder B. In this way gas is manufactured on the spot in quantities sufficient and of the quality necessary to properly supply the wants of the gas-engine.

25 When the engine is supplied from a carburetor, the burner K⁵ K⁸ K⁹ of the ignitor-valve is supplied with gasoline and feeds itself in any of the well-known modes.

The means for operating and controlling 30 the movement of said valves G, J, and H are as follows: On the valve-stem G⁵ below the valve-chamber of valve G is a spring N, and below the spring is a nut N'. The spring N is compressed between the valve-chamber and 35 this nut N'. By screwing the nut N' nearer to or farther from the valve-chamber the degree in which the spring is compressed is increased or diminished. A set-nut N² locks the nut N' after the latter has been located at the 40 desired place on the valve-stem. This spring N operates to seat the valve G at all times when the latter is not raised by the valve-lifter, soon to be described. This spring also performs the important office of resisting the 45 tendency of the valve to lift when a vacuum is formed in the conduit I by the downward movement of the piston B' in cylinder B. The stem J³ is provided with a spring N and nuts N' N², operating to keep the valve J seated whenever the latter is not lifted by 50 cam T. The pressure of gas in the cylinder B when compressed by the upward movement of the piston B' has a tendency to lift the valve, and this spring resists this tendency to 55 lift said valve. The stem H is also provided with a spring N and nuts N' N² for the purpose of keeping valve G seated when not lifted by its valve-lifter. This valve H has a 60 tendency to lift for the same reason that valve G does.

Various means for lifting the valves G, J, and H aforesaid may be employed. The preferred means of my invention are as follows: A shaft P is journaled on a bearing P', 65 connected to the frame-work A, and carries cam R, having an elongated working-surface. This cam operates valve G as follows: The

valve-stem G⁵ of said valve rests upon a stud G¹², fixed in a lifter G¹³, hinged at one end to pivot R², and carrying at its free end the 70 roller G¹⁴, the latter resting against the periphery of the cam R. The revolution of the cam R brings its working-surface R' into contact with roller G¹⁴ and lifts the latter, and with it lifts the lifter G¹³ and valve-stem G⁵. 75 The pivot R² is upheld by upright R³, fixed to the bearing P', in turn fixed to the bed or frame A. The valve-stem H³ is operated by lifter H⁷, hinged at one end to pivot-rod R², and carrying at its free end the roller H⁸, 80 resting upon the periphery of the said eccentric R. The working-surface R' of this eccentric R, as the latter rotates, comes in contact with roller H⁸, and lifts it and lifter H⁷ and valve-stem H³, thereby operating valve H. 85

The means for operating the ignitor-valve are as follows, viz: One end of a lifter J⁴ is pivotally suspended at J⁵ to a fixed stud J⁶ or equivalent portion of the engine. This stud J⁶ is in the present instance fixed to the piece 90 S, fixed to the side of the cylinder B. Arms S' S², fixed to said piece S, project horizontally under the valves, and through these arms pass and slide the valve-stems G⁵, J³, and H³. These arms steady the valve-stems, and with 95 the exception of valve-stem G⁵ in the instance hereinafter mentioned prevent the stems from any lateral deflection. The lifter J⁴ has a portion J⁷ extending to one side of the main portion of the said lifter, and it is this portion J⁷ which comes directly beneath the bottom of the valve-stem J³. The lifter J⁴ also carries a roller J⁸, which latter rests upon the cam T, fixed on said shaft P and having a working surface or point T'. As the cam T turns around, the point T' lifts roller J⁸, and the latter lifts the lifter J⁴, and thereby elevates the stem J³ and its valve J. It is desirable that the engine itself limit the supply of gas fed to it in order that it may not run 100 at a higher rate of speed than is desired, and also that it may retain a uniform rate of speed in spite of the different amounts of work placed upon it at different times, according to the various exigencies and demands of the 105 machine-shop, railroad-car, or other mechanism it is employed to operate.

The supply of gas can be regulated by a governor in connection with any of the well-known means. I prefer to employ in connection with the governor a device of my invention, at once novel, useful, and, on account of its simplicity, economy, and certainty of action, superior for my purposes to those now in use. This novel device will be described 110 in connection with the governor. V indicates the governor, of the usual form, fixed to a suitable support, and preferably fixed as shown to the upper part of the bearing P'. The lower portion of the vertical reciprocating 115 shaft of the governor is connected by a connection V' to the end of an arm of a right-angled lever, whose upper arm is at its free end connected to one end of the coupling-rod V³.

The other end of this coupling-rod V³ is connected to the stem G⁵. The opening in the bar S² which receives the stem G⁵ is wider in the direction of the length of the coupling-rod V³ than the thickness of the stem—viz., as shown by dotted lines in Fig. 3. The opening in the bar S' which receives the stem G⁵ is also widened sufficiently to allow the stem to oscillate the full length of said opening or slot in bar S². The width of the said openings in bars S' and S², is, however, only sufficient to admit said stem G⁵, thereby preventing the said stem from lateral oscillation to and from the cylinder B. When the engine is working at its normal speed, the lower end of stem G⁵ rests upon the stud G¹² of the lifter G¹³, and the engine then takes a fresh supply of gas at every revolution of the cam; but when the engine is running faster than its normal rate of speed the balls of the governor lift so that the vertical rod thereof is depressed, and such depression works the lever V² and advances the coupling-rod away from the stem G⁵, and consequently pulls stem G⁵ toward the left side of the engine when viewed as in Fig. 3, and off from the stud G¹². When the stem G⁵ is thus held, the lifter G¹³ will rise and fall without having operated the valve-stem G⁵ and valve G, because the stud G¹² will pass by the end of stem G⁵ and miss it. As soon as the speed of the engine has diminished to its normal rate, the balls of the governor will drop and the end of stem G⁵ will be brought again over the stud G¹², and the valve G will be again operated and the engine again regularly take a fresh supply of gas until the speed rises above the normal, when the foregoing operations of the governor-lever V² and stem G⁵ will be repeated. Thus the engine is easily kept running at a uniform and desirable rate of speed. When the engine is not working, the balls of the governor will fall and the stem G⁵ will be thrown out of contact with the stud G¹² on the left-hand side of said stud G¹².

When the engine is to be started, it is necessary that the stem G⁵ be compelled to engage the stud G¹² until the engine shall get into operation, and the governor shall take care of the stem G⁵, as aforementioned. For this purpose I employ a hook or equivalent detent G¹⁵, (see Fig. 15,) pivoted on the bar S'. Before starting the engine the stem G⁵ is moved directly over stem G¹², so as to directly impinge thereon. The hook G¹⁵ is now hooked around the stem G⁵, as shown in said Fig. 15, and the engine started. The hook thus keeps the stem G⁵ in working position over the stud G¹². When the engine is fully started, the hook G¹⁵ is thrown off and the governor will regulate the necessary impingements of the stud G¹² against the stem G⁵. Another position of such detent is shown by the dotted lines in said Fig. 15 below the figure in solid lines.

The manner in which my engine operates is in general as follows: Gas is first admitted

through the supply-pipe into the space G⁴ below valve G and the engine started. The cam R moves up over from right to left, as indicated by the arrow marked thereon. The working-surface R' of said cam R now lifts roller G¹⁴, lifter G¹³, stud G¹², stem G⁵, and valve G, thereby admitting fresh gas into the conduit I and to the upper end of the cylinder B. At the same time the piston B' is descending and the fresh gas admitted through valve G fills the enlarging space in the cylinder B above piston B' as the latter descends. At the time the piston B' has reached the lowest point of its stroke the working-surface R' of cam R will be just leaving the roller G¹⁴, and consequently the latter will descend and valve G will close. As the engine continues to operate, the piston B' rises and compresses the gas in the cylinder until it (the piston) reaches the upward point of its stroke, and then the working point T' of the cam T has reached the roller J⁸ and, lifting the latter, thereby lifts lifter J⁴, stem J³, and lifts the valve-piece J⁶ of the ignitor-valve. The fresh gas in the conduit I rushes up past the valve-piece J⁶, and coming into contact with the red-hot pipe K⁴ is lighted, and instantaneously burns backward into conduit I and cylinder B. Thus in an instant the gas in the cylinder B over the piston B' having been lighted, a great expansion of gas liberated by the combustion of the aforementioned gas takes place, and with force drives the piston downward. The ignitor-valve J after said ignition of gas immediately closes as the point T' of the cam T immediately leaves the roller J⁸. As the engine continues to operate and the piston begins again to rise, the working-surface R' of the cam R reaches the roller H⁸ and lifts the latter, thereby lifting lifter H⁷, stem H³, and the exhaust-valve piece H². The exhaust-valve H thus being opened, the volatile products arising from the consumed gas will pass out of said exhaust-valve. The working-surface R' of the cam R does not leave the roller H⁸ until the piston has reached the uppermost point of its stroke. The piston thus forces all of the volatile products of combustion remaining in the cylinder out of the exhaust. Thus nearly all of the said volatile products of combustion are thereby passed out of the cylinder B and conduit I. The working-surface R' of cam R now leaves roller H⁸, whereupon the exhaust-valve H immediately closes. The working-surface R' of cam R next immediately lifts roller G¹⁴ again and admits fresh gas to the conduit I and cylinder B. The foregoing operations are continually repeated, and thus the engine is operated. It will thus be observed that the cylinder takes gas at every other downward stroke and exhausts at every other upward stroke.

As is obvious from an inspection of the drawings, the shaft P is operated by the train of gear-wheels W W' W². The gear-wheel W' is fixed on the shaft P and engages the gear

W' on axis X', journaled in a bearing fixed to the frame, as shown by dotted lines in Fig. 1. This gear W' in turn engages the gear-wheel W, fixed to and rotated by the crank-shaft F'. The relative size of the wheels is proportioned as shown.

It may be here remarked that at the second elevation of the ignitor-valve piece J⁶ and at each subsequent elevation thereof the bad 10 gas—viz., the volatile products of combustion in the chamber or space J⁷—is driven up and out of the said chamber and through pipe K' and opening K³ of sphere K² by the fresh gas rushing from the conduit I past the lifted 15 valve-piece J⁶ and into said space J⁷, so as to turn the cams R and T relatively to the strokes of piston B', as hereinbefore described. Any other train of gear-wheels or pulleys or 20 equivalent mechanism suitable for thus rotating the cams aforementioned may be employed. The governor is also to be operated by any suitable mechanism. In the present 25 illustrative instance the governor is rotated by a pinion W³, meshing with the gear W², the shaft W⁴, turned by said pinion, directly operating the mechanism of the governor in the usual well-known manner and substantially as shown.

When carbureted air is to be supplied to 30 the machine, and a carburetor, as heretofore mentioned, is employed, a valuable saving of gasoline is effected from the fact that my engine draws just that amount of such gasoline needed for the operation of the engine, and 35 no more. The governor thus automatically (by means of the valve G) causes to be drawn from the carburetor just the amount of carbureted air sufficient to operate the engine and keep it running at a uniform rate of 40 speed. The valve L¹⁴ raises and lets down the gasoline whenever the governor determines such action shall take place. The purpose of the valve L⁴ is to operate the valve L¹⁴. The cock L¹¹ regulates the inflow of gasoline 45 to the space L¹⁰ and keeps the space supplied with gasoline, so that the valve L⁷ may let down all of the gasoline necessary for the operation of the engine.

The conduit I and the upper part of the 50 cylinder is kept hot when the engine is running. In this way the engine can use carbureted air, as the latter, when it enters the conduit I, is thereby kept in a gaseous form. Were the conduit I and the upper part of the 55 cylinder kept cool the carbureted air or gas would under the pressure present therein be condensed and liquid gasoline be formed in the said conduit I, and the engine would no longer operate.

60 A suitable water-jacket Z surrounds the cylinder as far up as the upper surface of the piston travels therein. An inlet-pipe Z' communicates with the lower part of the space of this water-jacket, and an exit-pipe Z² communicates with the upper portion of the space of this water-jacket. These pipes Z' Z² may be attached to a tank or other suitable con-

duits or vessels, so as to obtain a necessary circulation of water around said cylinder to keep the latter cool enough to allow the lubrication of said cylinder with oil.

While the various features of my invention are preferably employed together, one or more of said features may be employed without the remainder, and in so far as applicable one or 75 more of said features may be used in connection with gas-engines other than the one herein specifically described.

What I claim as new and of my invention, and desire to secure by Letters Patent, is— 80

1. In a gas-engine, the combination of the inlet-valve G, exhaust-valve H, conduit I, and ignitor-valve J, having passage-way J⁸ below the valve and communicating with conduit I and space J⁷ above the valve, connected, when the valve-piece J⁶ is elevated, with the said passage-way J⁸, tube K, located above space J⁷, pipe K' in contact with the said space J⁷ and passing through space K⁴ of the burner, and sphere K², communicating with pipe K' 85 and also having aperture K³, allowing egress of the gas within into the outer air, substantially as and for the purposes specified.

2. In a gas-engine, the combination of the inlet-valve G, exhaust-valve H, conduit I, said inlet-valve and exhaust-valve opening into said conduit, ignitor-valve J, having passage-way J⁸ below the valve and communicating with conduit I, space J⁷ above the valve, connected, when the valve-piece J⁶ is elevated, with the said passage-way J⁸, tube K, located above the space J⁷, and pipe K' in contact with the said space J⁷ and passing through space K⁴ of the burner, the tube K having the annular lining of non-heat-conducting material surrounding the pipe K' above said burner-space K⁴, substantially as and for the purposes specified.

3. The combination, with a gas-engine and with the supply-pipe leading thereto, of a carburetor having an air-pipe opening upwardly therein, a gravity-valve covering said pipe and lifted by the suction in the engine-supply-pipe, and an oil-valve engaging the air-valve and lifted thereby to pass oil to the surface of the air-valve, whence it is distributed by the air-current, all substantially as described.

4. In a gas-engine having a governor and an air and gas supply pipe, a carburetor communicating with said supply-pipe, a feeding-valve in said carburetor operated by the suction in the supply-pipe, and an air-controlling valve in the supply-pipe, itself controlled by the governor, whereby the suction in the supply-pipe, and hence the carbureted supply, is controlled by the governor, substantially as described.

5. The combination, with a gas-engine and the supply-pipe thereof, of a carburetor communicating with said supply-pipe opening upwardly into said carburetor, a gravity air-valve covering said pipe and operated by suction in the engine-pipe, a liquid-controlling valve engaging said air-valve and operated

thereby to feed liquid upon the surface of said air-valve, and carbureting-rings in proximity to said air-valve, substantially as described.

5 6. The combination, with the suction-pipe of a gas-engine, of the carburetor having the delivery-pipe L' , connected to said suction-pipe, and having the exterior shell L , interior tube or hollow cylinder L^2 , carbureting-rings L^{13} 10 between said shell L and said cylinder L^2 , communicating with the outer air and provided with valve-piece L^4 resting upon it, valve-stems L^5 and L^{14} , valve-piece L^7 , lifted by valve L^4 , spaces $L^8 L^9$ for the passage of 15 oil past the valve-piece L^7 when the valve is lifted, space L^{10} above the valve-piece L^7 , and inlet-valve, substantially as and for the purposes specified.

7. In a gas-engine, a governor, and the gas-supply valve G , swinging-valve stem G^5 beneath the valve G , vertically-reciprocating stud G^{12} , and lever V^2 , connected to the governor and to stem G^5 , substantially as and for the purposes specified.

25 8. In a gas-engine, the inlet-valve G and its supporting-stem G^5 , the valve-lifter G^{13} , exhaust-valve H and its supporting-stem H^3 , valve-lifter H^7 , and the single cam R , having working-surface R' for both valves, substantially as and for the purposes specified.

9. In a gas-engine, the inlet-valve G , its lifter G^{13} , and exhaust-valve H and its lifter H^7 , the lifters hinged on the common pivot R^2 and both engaging the same cam R whose 35 shaft P is at right angles to the common plane passing through the valves, substantially as and for the purposes specified.

10. In a gas-engine, the inlet-valve G , its lifter G^{13} and roller G^{14} , and exhaust-valve H 40 and its lifter H^7 and roller H^8 , the lifters hinged on the common pivot R^2 and both engaging the same cam R whose shaft P is at right angles to the common plane passing through the valves, substantially as and for the purposes specified.

45 11. In a gas-engine, the gas-inlet valve, exhaust-valve, and ignitor-valve, and their lifters, and the cams R and T on a common shaft and operated thereby, the cam R in contact with the lifters of the inlet and exhaust valves and cam T in contact with the lifter of the ignitor-valve, substantially as and for the purposes specified.

12. In a gas-engine, the gas-inlet valve and 55 conduit I , leading therefrom to that part of

the cylinder which is above the upper stroke of the piston and above the said upper part of the cylinder, the said gas-inlet valve being arranged for the admission of air and a volatilized hydrocarbon, the exhaust-valve 60 located in conduit I between said gas-inlet valve and the working-cylinder, and an ignitor-valve located in said conduit I between the gas-inlet valve and the exhaust-valve, thereby heating those parts of conduit I 65 through which the commingled unignited air and volatilized hydrocarbon pass on their way to the cylinder, thereby preventing any condensation of the carbureted air under pressure in said conduit and cylinder, substantially as and for the purposes specified.

13. In a gas-engine, the gas-inlet valve and conduit I , leading therefrom to that part of the cylinder which is above the upper stroke of the piston and above the said upper part 75 of the cylinder, the said gas-inlet valve being arranged for the admission of air and a volatilized hydrocarbon, the exhaust-valve located in conduit I between said gas-inlet valve and the working-cylinder, and an ignitor-valve located in said conduit I between the gas-inlet valve and the exhaust-valve, thereby heating those parts of conduit I 80 through which the commingled unignited air and volatilized hydrocarbon pass on their way to the cylinder, thereby preventing any condensation of the carbureted air under pressure in said conduit and cylinder, and the cylinder below the uppermost point therein reached by the piston being in contact with 90 a water-jacket Z for keeping the lower portion of the cylinder wherein the piston plays at all times cool and in proper condition for lubrication with oil, substantially as and for the purposes specified.

14. A gas-engine having an inlet suction-pipe, in combination with a carbureting device consisting of the exterior shell L , gas-exit pipe L' , connected thereto and to the said suction-pipe of the engine, air-inlet pipe controlled by valve L^4 , valve L^4 , inlet gasoline-valve L^7 , and means, substantially as herein set forth, for enabling said air-inlet valve L^4 to operate said gasoline-inlet valve L^7 , substantially as and for the purposes specified. 105
